(57) **CLAIM**

The ornamental design for a beverage locking cap for use with a beverage locking device, as shown and described.

DESCRIPTION

FIG. 1 is a perspective view of a beverage locking cap for use with a beverage locking device showing my new design; FIG. 2 is a front view thereof;

FIG. 3 is a side view thereof;

FIG. 4 is a bottom view thereof;

FIG. 5 is a top view thereof; and,

FIG. 6 is a perspective view thereof, the locking cap shown engaged with a beverage locking device and bottle shown in broken lines.

The broken line showing of a beverage locking device is for illustrative purposes only and forms no part of the claimed design.
